UNITED STATES PATENT OFFICE.

EMANUEL HAMMERLING, OF NEW YORK, N. Y.

DESIGN FOR A LADIES' HAND BAG.

Application filed April 11, 1928. Serial No. 26,276. Term of patent 7 years.

To all whom it may concern:

Be it known that I, EMANUEL HAMMERLING, a citizen of the United States of America, residing in the borough of Manhattan, city, county, and State of New York, have invented a new, original and ornamental design for a Ladies' Hand Bag, of which the following is a specification, reference being had to the accompanying drawing, forming a part thereof.

The drawing is a perspective view of ladies' hand bag illustrating my new design.

I claim:

The ornamental design for a ladies' hand bag, substantially as shown.

This specification signed this 4th day of April, 1928.

EMANUEL HAMMERLING.
